UNITED STATES PATENT OFFICE.

THOMAS W. MOORE, OF PLAINFIELD, NEW JERSEY.

VESTIBULE-CAR.

SPECIFICATION forming part of Letters Patent No. 417,496, dated December 17, 1889.

Application filed September 9, 1889. Serial No. 323,467. (No model.)

To all whom it may concern:

Be it known that I, THOMAS W. MOORE, a citizen of the United States, and a resident of Plainfield, Union county, New Jersey, have 5 invented new and useful Improvements in Vestibule-Cars, of which the following is a specification.

My invention consists of the improvements in the construction and arrangement of vestibule-cars hereinafter described and claimed, 10 reference being made to the accompanying drawings, in which—

Figure 1 is partly a side elevation and partly a longitudinal section of my improved 15 vestibule devices for providing inclosed passages between cars in a train. Fig. 2 is a horizontal section of the same. Fig. 3 is a detail of the vestibule sides in top view and on an enlarged scale.

20 In vestibule-cars heretofore made the vestibule-passage has generally been limited in breadth to the width of the door in the end of the car, or thereabout, and at most to the width between the platform-steps, which is 25 not as desirable nor effective of the purpose of vestibules as more ample space between the sides will afford. Such limitation has been due mainly to the contracted upper surface of the platform by the steps.

30 It is my purpose to construct the vestibule as wide as the interior space of the car, or nearly so, and to this end I provide trap-doors *a* to close down over the steps *b*, and thus practically widen the platform top to 35 the full breadth of the car, and I hinge the end portions of the car *c* each side of the middle space for the door to the ends of the car sides at *d*, so as to constitute folding doors to 40 swing outward to the planes of the car sides and form the principal portions of the vestibule sides—say to the length of the platforms—with the usual door-bolts *f* to fasten them at 45 *e* when it is desired to displace the vestibule and close the ends of the cars. The same or any other approved means may be employed to fasten said doors *c* in the open position. In this example they are represented as opening against the sides of posts *f*, to which they 50 may be fastened, if desired.

50 The trap-doors *a* are hinged at *g* to swing up either to the inside or outside of the folding doors *c* when they are closed. To close the middle space at such time, I provide the

sliding door *h*, which may then be shifted to the middle space; and when a closet *i* is to 55 be provided at one side of said middle space I provide the hinged door *j*, arranged to swing open against the side of the closet, thus leaving the whole space between the closet and the other side of the car open. For the same 60 purpose I arrange the slide-door *h*, when it is used to slide across to the other side, behind the closet when the vestibule is to be used.

For extending the platforms across the space between the ends *k* of the same, I provide 65 the beams *l*, hinged to the platforms *k* at *m*, and meeting together at the middle of the space between said ends when the cars are coupled. Said beams are curved on the sides adjacent to the platform ends, reversely 70 to the curves of said ends, so that while they retain their position practically the ends of the platform rock on them as the train swings on curves, and said beams have an extension-plate *n* or rack *o*, which extends a suitable 75 distance under the top plate *p* of the platform front, making an extending and contracting floor as the cars vibrate. Over these beams is a plate *q*, covering the joint between them, said plate being flush with 80 the top plates *p* of the platforms and being coupled to the ends of the platform by the joint-bolts *m*, also coupling the beams *l*. The holes *s* in said plate for the joint-bolts are elongated to allow for the independent lateral 85 play of the cars. This is not necessary with the beams *l*, as they are not connected together, but are free to shift lengthwise relatively to each other.

The top plates *p* and the intermediate plate 90 *q* are to be of such thin metal that should one tread on the plate *n* or rack *o* between them while the swing of the train were closing the joint between plate *q* and a plate *p* the edges suitably beveled would be forced under the sole of the shoe without material injury thereto; but these joints may be covered with leather, canvas, rubber, or other suitable material, or the whole may be covered with a thin metal plate. 95

At the extremities of the beams *l* they have each a small stanchion *t*, the contiguous stanchions having bearing-contact like the beams at the meeting point, and they are made broad in the bearing-surfaces to avoid opening the joint by the independent lateral play 100 105

of the cars, and said surfaces are preferably padded with rubber f' , in corrugated or other like condition, to make the joint tight. At the upper ends and elsewhere, if desired, these stanchions may be coupled by any approved yoke g' , allowing lateral play, but maintaining the face contact, which keeps the joint closed. At the lower end this contact is maintained by the beams l , on which the stanchions are inserted. To these stanchions rubber, leather, or other sheets of flexible material u are buttoned or otherwise connected at one edge, and at the other edge they are connected to spring-rollers v within the posts f , said posts being hollow and having a slit w , through which the flexible sheets are drawn taut by the recoil of the springs, and they play forward and backward according as the cars swing on the curves.

20 While it is preferable to inclose the spring-rollers in the hollow posts, they may be arranged exterior to said posts, or the rollers may be used without the posts, said rollers being mounted on the platform and supported at the upper end by the extension-roof of the car, or they may be mounted on the folding-door ends of the car. To provide for ingress and egress without shifting these folding-door ends of the car from their positions at sides of the 25 vestibule, they are made with suitable openings y from the bottom upward a suitable distance, to afford passage when the trap-doors are raised, and said openings have other doors x , to close them, said doors being hinged to folding-doors c at z , so that they open and close said passages, as desired. The trap-doors will be raised first, preferably, and fastened up, then doors x will be opened, and thus the passage for ingress and egress will be as free as 30 without the vestibule. To close the space between the roof-extensions a' overhead, I provide a rubber sheet b' , in suitable form and dimensions to be hooked or buttoned at the opposite ends under the roof, as indicated at c' , said sheet being shortest in the middle and increasing in length therefrom each way to the sides suitably for the greater range required at the sides by the swing of the cars on the curves, and so that it will not sag uniformly at the middle when there is little or no variation of the distance between the ends of the roofs. The sides of this flexible top sheet will hang in folds over the upper ends of the side webs n and effect suitable inclosure thereat, as will be understood by reference to Fig. 1.

35 What I claim, and desire to secure by Letters Patent, is—

1. In vestibule-cars, the car ends consisting of folding doors opening the width of the cars and over the steps, and said steps covered by trap-doors.

2. In vestibule-cars, trap-doors covering the steps, in combination with the car ends consisting of folding doors opening over the steps so covered by the trap-doors.

3. In vestibule-cars, the car ends consisting of folding doors hinged to the ends of the car sides, opening the width of the cars over the steps covered by trap-doors, and forming the essential portions of the vestibule sides.

4. In vestibule-cars, the car ends consisting of folding doors opening the width of the cars over the steps covered by trap-doors and forming the essential portion of the vestibule sides, and also having other doors, which, together with the trap-doors, afford passage through the folding-door vestibule sides.

5. In vestibule-cars, the folding-door car ends forming the essential portions of the vestibule sides, and flexible connecting-webs connecting the folding doors of the respective cars and completing the vestibule sides.

6. In vestibule-cars, the folding-door car ends forming the essential portions of the vestibule sides, the flexible connecting-webs connecting the folding doors of the two cars, and spring-rollers automatically controlling the flexible webs.

7. The flexible web-sections of the vestibule sides, connected at one end to the spring-rollers at the extremity of the platform and at the other end connected to the stanchions supported on the intermediate floor-beams.

8. The flexible web-sections of the vestibule sides, connected at one end to the spring-rollers on the extremities of the platform and at the other end connected to the stanchions having the rubber or other packed contact faces.

9. The intermediate floor-plate, combined with the intermediate beams pivoted to the platform ends and having bearing contact, and provided with the extension-plates projecting under the platform top plates.

10. The flexible cover-sheet suspended under the ends of the extension-roofs and hanging over the upper ends of the flexible sections of the vestibule sides.

11. The combination, with the folding-door car ends, of a door to close the middle space when said folding doors are closed, having support independently of said folding doors.

12. The combination, with the folding-door car ends and a closet located within and in close proximity to said end when closed, of a door for closing the middle space opening to one side of the closet.

13. The vestibule sides extended over the steps covered by trap-doors and each having a passage-way over the steps, and a hinged door thereto, swinging over the trap-door, for opening and closing the same.

In testimony that I claim the foregoing as my invention I have signed my name, in presence of two witnesses, this 29th day of August, 1889.

THOMAS W. MOORE.
